CLAIM

The ornamental design for a baby pacifier, as shown and described.

DESCRIPTION

FIG. 1 is a rear elevation view of a baby pacifier, showing my new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is left side, front and top perspective view thereof; and,

FIG. 8 is left side, back and bottom perspective view thereof. In the drawings, the equal-length broken lines depict portions of the baby pacifier that form no part of the claimed design.

1 Claim, 4 Drawing Sheets
